UNITED STATES PATENT OFFICE

ALFRED F. MASURY, OF NEW YORK, N. Y., ASSIGNOR TO INTERNATIONAL MOTOR COMPANY, OF NEW YORK, N. Y., A CORPORATION OF DELAWARE

DESIGN FOR AN INCLOSED AUTOMOBILE CAB

Application filed December 9, 1930. Serial No. 37,927. Term of patent 14 years.

To all whom it may concern:

Be it known that I, ALFRED F. MASURY, a citizen of the United States, residing in the borough of Manhattan, of the city of New York, in the State of New York, have invented a certain new, original, and ornamental Design for Inclosed Automobile Cab, of which the following is a specification, reference being had to the accompanying drawings, forming a part hereof.

ing a motor vehicle cab embodying the design of the present invention.

I claim:

The ornamental design for an inclosed automobile cab, as shown.

This specification signed this 5th day of December A. D. 1930.

ALFRED F. MASURY.
